INVENTOR
BY
Victor J. Evans
ATTORNEY

UNITED STATES PATENT OFFICE.

WILBUR BELL, OF MARENGO, IOWA.

STAMP-INKING PAD.

Application filed January 9, 1922. Serial No. 528,032.

To all whom it may concern:

Be it known that I, WILBUR BELL, a citizen of the United States, residing at Marengo, in the county of Iowa and State of Iowa, have invented new and useful Improvements in Stamp-Inking Pads, of which the following is a specification.

This invention relates to stationery apparatus, particularly to inking pads for rubber stamps and the like, and has for its object the provision of an inking pad of novel construction which is so formed as to provide ample means for retaining a sufficient quantity of ink to be applied to the rubber stamp 15 or the like when the same is pressed thereupon, the device furthermore including an absorbent covering which will operate to prevent the adhesion of more than the proper quantity of ink onto the rubber stamp and 20 consequently preventing smearing at any time.

Another object is the provision of a pad of this character which has for a specific detail the provision of a pad formed primarily 25 of a rubber sponge which has a high degree of absorbing ability so as to contain a relatively large amount of ink which will last quite a while.

An additional object is the provision of a 30 pad of this character which will be simple and inexpensive in manufacture, highly efficient in use, durable in service and a general improvement in the art.

With the above and other objects and advantages in view, the invention consists in the details of construction to be hereinafter more fully described and illustrated in the accompanying drawings in which,

Figure 1 is a perspective view of a pad 40 constructed in accordance with my invention and

Figure 2 is a sectional view therethrough.

Referring more particularly to the drawings I have shown my device as comprising 45 an outer receptacle or container 10 provided with the usual cover 11 which may be either of the hinged or slipped type. Located within this container and suitably secured therein if so desired, is the pad proper which consists of a base 12 which is a rigid plate and

which may be a block of wood if preferred. Mounted upon this base is preferably a sheet of absorbent material 13 such as blotter and superposed upon this absorbent element is a rubber sponge 14 of any desired thickness 55 and which is adapted to be more or less saturated with the ink to be used. Disposed upon top of the rubber sponge is a sheet 15 of felt which is likewise absorbent. The elements 12, 13, 14 and 15 are preferably enclosed within a fabric covering 16 which may be comparatively thin cloth so as to present a relatively smooth surface upon which the rubber or other stamp to be inked may be pressed. 60

In the use of the device it is to be observed that ink of the usual kind employed for this purpose is poured upon the pad and will soak through the cover 16, felt 15 and into the sponge 14 where it will be retained. 70 When a stamp is pressed upon the exposed surface of the fabric 16 it is apparent that a certain quantity of the ink will be pressed out of the sponge and will serve to coat the printing surface of the stamp with a thin 75 film. When pressure upon the pad is relieved it is apparent that the subsequent expansion of the rubber sponge will operate to suck back into itself any surplus ink which have been drawn to the surface by the previously applied pressure. In this way it will be seen that the device will supply only a small quantity of ink to the stamp. 80

From the foregoing description and a study of the drawings it will be apparent 85 that I have thus provided a very simply constructed and consequently inexpensive inking pad which will be very highly efficient in use and which is so constructed that various parts might be separated for effecting 90 cleansing if such should be desired. Owing to the simplicity of the construction it is apparent that there should be no trouble with the device and it should efficiently perform all the functions for which it is intended. 95

While I have shown and described the preferred embodiment of the invention, it is of course to be understood that I reserve the right to make such changes in the form, 100

2
construction and arrangement of parts as will not depart from the spirit of the invention or the scope of the subjoined claims.

Having thus described my invention I 5 claim:

An inking pad comprising a containing receptacle provided with a cover, a base of rigid material mounted within the recep-

tacle, a sheet of blotter mounted upon the top of the base, a rubber sponge disposed upon the blotter, a sheet of absorbent felt disposed upon the top of the sponge, and a fabric covering for the sponge, felt and base.

In testimony whereof I affix my signature.

WILBUR BELL.
